UNITED STATES PATENT OFFICE.

EDWIN HENRY COLPITTS, OF EAST ORANGE, NEW JERSEY, ASSIGNOR TO WESTERN ELECTRIC COMPANY, OF NEW YORK, N. Y., A CORPORATION OF ILLINOIS.

ELECTRIC-WAVE AMPLIFIER.

1,128,292.

Specification of Letters Patent. Patented Feb. 16, 1915.

Application filed January 3, 1914. Serial No. 810,196.

To all whom it may concern:

Be it known that I, EDWIN HENRY COLPITTS, a subject of the King of Great Britain, residing at East Orange, in the county 5 of Essex and State of New Jersey, have invented a certain new and useful Improvement in Electric-Wave Amplifiers, of which the following is a full, clear, concise, and exact description.

- 10 This invention relates to electric wave repeating apparatus and particularly to the use of vacuum discharge repeaters as exemplified by the so-called "audion" for repeating and amplifying in an output circuit waves of electric energy received in an input circuit. Its object is to improve 15 the quality of transmission by producing in the output circuit electric waves free from distortion with respect to the input waves.
- 20 The invention is especially useful in telephone and telegraph service for repeating and amplifying alternating current waves of small magnitude.

The principal parts of an audion element 25 or structure are a heated filament or other source of ionization, an anode usually called a "plate," and an intermediate electrode usually called a "grid." These are preferably inclosed in an evacuated glass vessel.

30 Characteristic features of the audion are that current can flow in one direction only in the ionized stream, and that the strength of current in the stream flowing from its source to the plate is modified by electro- 35 static rather than by electromagnetic force as in some other types of "gaseous" repeaters.

A simple arrangement for using a single audion element as a repeater is as follows: 40 The input circuit is connected, one side to the filament and the other to the grid, while the output circuit is connected, one side to the filament and the other to the plate. Repeating coils are preferably employed to the 45 input and output circuits respectively, and a battery is included in the output circuit in series with the primary winding of the output repeating coil. The audion repeater as thus used, although a powerful amplifying agent, does not repeat in the output circuit a perfect form reproduction of the electric wave received in the input circuit. This is due to the fact that the space between the filament and the grid has unilateral conductivity. When an alternating

potential is applied between the filament and the grid, current flows during that part of each wave cycle in which the grid is positive, but little or no current flows in this circuit during the other part when the grid 60 is negative. This unsymmetrical action results in a certain amount of distortion in the output waves which is avoided, in accordance with this invention, by employing two audion elements, one of which operates 65 to repeat the positive parts and the other the negative parts of the input waves. Two structurally separate elements of the audion type may be employed or two such elements may be combined in one structure for this 70 purpose.

In the drawings Figure 1 represents a system of circuits including two separate audion structures combined in accordance with the invention; Fig. 2 represents a system of circuits including two audion elements combined as a single structure and in such a way as to utilize a common source of ionization; Fig. 3 represents a commercial telephone line equipped with one repeater set for two-way service; Fig. 4 represents another commercial system of circuits for telephonic transmission in which the line is divided and each part equipped with a separate repeater set, and Fig. 5 is 80 a perspective view of a single structure comprising two audion elements adapted for the systems shown in Figs. 2, 3 and 4.

The same reference characters are used to designate like parts in the several figures. 90

Incoming and outgoing conductors to and from the repeating apparatus of this invention are represented in the several views by the wires 1, 2 terminating in the primary winding 3 of an input repeating coil 4, and the wires 5, 6 terminating in the secondary winding 7 of an output repeating coil 8 respectively. The secondary winding of the repeating coil 4 is divided into two coils 9 and 10, and the primary winding of the repeating coil 8 is divided similarly into two coils 11 and 12. Two audion elements are combined and included in each of the circuits. They comprise two heated filaments 13 and 14 (13 only in Figs. 2, 3 and 4); 100 two anodes or plates 15 and 16, and two intermediate electrodes or grids 17 and 18. The filaments are heated by current from the battery 19 and the output circuit, including the primary coils 11 and 12 of the 110

repeating coil 8, has included in a common portion of it a battery 21. In each of the systems, shown in Figs. 1 to 4, there are employed three classes of circuits exclusive of the incoming and outgoing line circuits. 5 One is the circuit of the heated filaments fed by the battery 19. The second is the divided input circuit which includes the coils 9 and 10 of the secondary winding of 10 the repeating coil 4, the grids 17 and 18 oppositely connected in said circuit, a portion of the ionized stream and the filament or filaments. The third is the divided output circuit which in Fig. 1 includes in the common portion the battery 21 and in the divided portions the heated filaments 13, 14, the ionized streams, the anodes 15, 16, and the primary coils 11, 12 of the repeating coil 8. In Figs. 2, 3 and 4 the single filament 20 13 is in the common portion of this circuit.

In Fig. 3, a telephone line is represented in which one repeating set of two audion elements may be employed to provide for commercial two-way telephonic transmission between two stations 48 and 49. The circuit arrangement is the same as that of Figs. 1 and 2 except that the primary winding 3 of the input repeating coil 4 is divided into 25 four coils, as shown, and its several coils are included serially in the telephone line, while the secondary winding 7 of the output repeating coil 8 is placed in bridge of the telephone line and connected symmetrically with 30 respect to the several coils of the primary winding 3.

In Fig. 4 are shown two repeating sets A and B to provide, in another way, for commercial two-way service. The telephone line 40 is divided and the two parts separately balanced by networks 46 and 47, respectively. The primary winding 3 of the input repeating coil 4 of the repeater sets A is divided into four coils which are included serially in 45 the telephone line extending between the telephone station 48 and the network 46. In the same way four coils of the primary winding 3 of the repeating coil 4 of the other set B are included serially in the line 50 extending between the telephone station 49 and the network 47. In the system of Fig. 4, telephonic currents generated at station 48 are repeated by the set A and reproduced in the line to station 49, while telephonic currents generated at station 49 are likewise 55 repeated by the set B and reproduced in the line to station 48.

The operation is as follows: Telephonic currents or other electric current waves 60 coming by way of conductors 1, 2 are received in the primary winding 3 of the input repeating coil 4, and reproduced by the coils 9, 10 of the secondary winding thereof in the input circuit. At any instant of time, except 65 of course at the moment when a wave is

passing the point of zero current flow, there will be positive potential impressed on one of the grids, say 17, and a corresponding negative potential impressed on the other grid, 18. As current can flow between the 70 heated filament and the grid of either audion element only when the grid is at positive potential with respect to the filament, the effect on the current in the ionized stream flowing between the filament and plate will 75 be different in the two audion elements. The grid, which is for the moment positive, will materially alter the flow of current in the stream in which it is interposed, but the grid, which at the same moment is negative, 80 will have little or no effect. As the electric current wave progresses in the input circuit, the potential conditions on the two grids become reversed so that the negative portion of the wave (assuming the other 85 portion considered to have been positive) will be repeated due to positive potential on the previously ineffective grid. Thus every variation in current produced by the input waves is repeated by one or the other of the 90 two audion elements.

A suitable structure for the two audion elements when combined in one is shown in Figs. 3 and 4, wherein the filament 13 is supported from one end of the glass bulb or 95 vessel 34, the leading-in wires to the filament being connected to the tip and sleeve terminals respectively of an ordinary lamp socket plug 44. The two grids 17, 18 and two plates 15, 16 are supported at the other end of the 100 vessel and held in their proper positions by a forked glass support 35. The upper ends of the grids are attached by means of short wires 36, 37 to the upper ends of the support 35. The plates 15, 16 are centrally supported 105 by bow shaped wires 38, 39 respectively. Leading-in wires 40, 41, 42 and 43 are provided for connecting the grids and plates in circuit, and the portions of these wires on the inside of the vessel 34 aid in their support. 110

What is claimed is:

1. An electric wave repeating apparatus comprising divided input and divided output circuits, means for producing two ionized streams, said streams being oppositely included in said output circuit, and two electrodes for controlling said ionized streams respectively and oppositely connected in said input circuit. 115

2. An electric wave repeating apparatus comprising divided input and divided output circuits, means for producing an ionized stream included in each division of said output circuit, and electrodes, one in each 120 division of said input circuit for controlling said ionized streams respectively.

3. An electric wave repeating apparatus comprising input and output circuits and two vacuum discharge repeater elements 130

oppositely connected in said circuits, whereby the positive and negative portions of electric waves in said input circuit are repeated by said repeater elements respectively in said output circuit.

4. In an electric wave repeating apparatus, the combination with input and output circuits, of two vacuum discharge repeater elements oppositely connected in said circuits whereby one of said elements is adapted to repeat certain parts, and the other, the remaining parts of said input waves.

5. In an electric wave repeating apparatus, the combination of two repeating elements comprising ionizing means, an anode and an input electrode for each said element, an input repeating coil the secondary winding of which is connected at an intermediate point to said ionizing means and at its opposite terminals to said input electrodes respectively.

6. In an electric wave repeating apparatus, the combination of two repeating elements comprising ionizing means and an anode and an input electrode for each said element, an input repeating coil and an output repeating coil, the secondary winding of said input repeating coil being divided

and the divisions connected to said input electrodes respectively, and the primary winding of said output repeating coil being divided and the divisions connected to said repeating elements respectively.

7. In an electric wave repeating apparatus, the combination with input and output circuits and a repeating coil in each of said circuits, of two repeating elements together comprising a common source of ionization, an anode for each said element, and two input electrodes, said source of ionization being connected to an intermediate point in the secondary winding of the input repeating coil and also to an intermediate point in the primary winding of the output repeating coil, the opposite terminals of said secondary winding being connected to said input electrodes respectively, and the opposite terminals of said primary winding being connected to said anodes respectively.

In witness whereof, I hereunto subscribe my name this 31st day of December A. D., 1913.

EDWIN HENRY COLPITTS.
